FIG. 1 is a perspective view of a phonograph front panel showing our design, in which the broken lines indicate the environmental structure.

FIG. 2 is a front elevation of one of the basic elements making up the panel shown in FIG. 1 and drawn on an enlarged scale.

FIG. 3 is a left side elevation of the element shown in FIG. 2 taken along the line 3—3 of FIG. 2, the views from the other side being the same or a mirror image.

FIG. 4 is a sectional view of the element shown in FIG. 2 taken along the line 4—4 of FIG. 2.

FIG. 5 is a sectional view of the element shown in FIG. 2 taken along the line 5—5 of FIG. 2.

FIG. 6 is a sectional view of the element shown in FIG. 2 taken along the line 6—6 of FIG. 2.

We claim:

The design for a phonograph front panel, substantially as shown and described.
